UNITED STATES PATENT OFFICE.

SAMUEL F. TAPPAN, OF SAN FRANCISCO, CALIFORNIA.

POWER STEERING APPARATUS FOR VESSELS.

SPECIFICATION forming part of Letters Patent No. 224,364, dated February 10, 1880.

Application filed February 7, 1879.

To all whom it may concern:

Be it known that I, SAMUEL F. TAPPAN, of the city and county of San Francisco, in the State of California, have invented a certain new and useful Power Steering Apparatus for Vessels; and I do hereby declare that the following is a full, clear, and exact description of my invention, reference being had to the drawings forming part of this specification.

This invention relates to steering gear or apparatus for vessels, and it is of that class designed to be worked by power. It is applied to or combined with the steering-wheel or its drum, and is operated by power transmitted from the engine-room through an endless belt.

Its object is to provide a steering apparatus by which the rudder is placed under complete control, not only of the man in the wheel-house, but also of the officer on the bridge or the deck above, which serves and operates at all times to indicate to the steersman and to the officer on the bridge the exact position of the rudder, and which possesses, besides, great simplicity of construction, economy both in the motive power required to run it and in the space needed for it in the wheel-house, and facility and rapidity of operation, all which will be more fully set forth hereinafter.

The principal elements of my invention consist of a horizontal shaft held in bearings in close position to the steering-drum and geared into the drum or the steering-wheel, an arrangement of loose pulleys revolved continuously and in opposite directions to each other upon said shaft, a means for locking said pulleys one at a time to said shaft to give it motion in either direction at will, and a means for operating said locking mechanism both from the station in the wheel-house and from the bridge or deck above; also, in connection and combination with the drum, steering-wheel, or other part of a steering-gear of a vessel, a means for recording or showing the movements of the rudder and indicating its position at all times to the man at the wheel and the officer on the bridge or the deck above; also, in combination with the mechanism for moving the rudder, a friction brake or brakes to hold the steering-drum stationary at any point when the rotating mechanism is thrown out of action.

To more fully understand the nature of my invention, and the manner of constructing and applying it, the accompanying drawings are 55 herein referred to by letters and figures.

Figure 1 is an elevation, in longitudinal section, of a wheel-house and steering-wheel with my invention applied thereto. Fig. 2 is a front elevation of my apparatus. Fig. 3 is 60 a detail view of the auxiliary hand-lever. Fig. 4 is an elevation, in detail, of the principal shaft, with its pulleys, clutches, and operating mechanism. Fig. 5 is a view, partly in section, 65 taken through the line $x' x'$, Fig. 4. Fig. 6 is a detail view of the friction-clutches and their levers. Fig. 7 shows the construction of the axial sleeve between the clutches. Fig. 8 is a detail view of the pivoted plate between the levers. Fig. 9 is a detail view in horizontal 70 section, taken in the line $y' y'$, Fig. 4. Fig. 10 shows the levers and brakes. Fig. 11 shows, in detail, the parts that indicate the movements of the rudder.

The wheel-house A, the wheel C, and the 75 drum or axle D are all of the ordinary kind now in use, and no change is required to apply my invention to any steering-gear already constructed. Between the standards B B, I place a suitable supporting-frame, E E, firmly 80 secured to the floor of the wheel-house, in which are suitable bearings for a horizontal shaft, a. Upon the end of this shaft, outside of the bearing E, I fix a pinion, b, to work into a gear-wheel, F, that is either bolted to 85 the arms of the steering-wheel or is secured upon its axle. Upon the shaft a, between the bearings E E, are two loose pulleys, G G', that are free to revolve independently of each other, and these pulleys are driven continuously from a shaft or a motor located in the engine-room of the vessel by means of an endless belt, H, that runs over one pulley, G, around beneath a pulley, g, and back over the other pulley, G', and they are thus rotated in 90 opposite directions, one to the right and the other to the left.

I I' are two friction disks or clutches fixed upon and turning with the shaft a or rather turning it when either one of them is locked 100 to one of the continuously-rotating pulleys. They are capable of being moved laterally upon the shaft, but are held at a fixed distance from each other, and are shifted forward

or back simultaneously together. They occupy a position on the central part of the shaft equidistant from both pulleys G G', and the shaft does not move except as one or the other 5 of the clutches is moved up and pressed against its corresponding pulley.

As long as this contact of a clutch and a pulley is maintained the shaft *a* will revolve and turn the gear *F* and bring the rudder 10 around either to port or to starboard. The movement of one clutch against its pulley *G* or *G'* causes the shaft *a* to revolve in one direction, while the movement of this clutch away from its pulley and the contact of the 15 opposite clutch with the pulley next to it produces a revolution of the shaft in the other direction. The position of these clutches *I I'* when the rudder is to be held at rest at any point is upon the center part of the shaft *a*, 20 equidistant between and out of contact with the two continuously-revolving pulleys, and therefore while the belt *H* is driving the pulleys *G G'*, one to the right and the other to the left, no motion is given to the shaft *a*, except as one or the other of the clutches *I I'* is 25 moved and held against its pulley.

These several parts—the two continuously-revolving pulleys driven by power transmitted from the engine-room, the shaft *a*, geared into 30 a wheel on the steering-drum, and the shifting frictional clutches for locking the shaft to either one of the pulleys—constitute the principal elements of my apparatus; and for the purpose of properly operating them I employ 35 in connection and combination therewith a means for moving the clutches *I I'* either in the wheel-house or from the bridge or the deck above; also, a means of holding the shaft *a* at rest at any point as soon as the clutches are 40 thrown out of action; also, a means for throwing the clutches automatically out of action and stopping the movements of the shaft *a* whenever the rudder reaches its extreme position either to port or to starboard, and a 45 means for automatically moving the operating levers or handles simultaneously and in unison with the rudder, so that as the rudder changes its position with respect to the line of the keel so do the hand-levers change their 50 position with respect to a fixed mark or index, and both the rudder and its operating-levers always keep the same line or angle.

The clutches *I I'* are moved into and out of action by means of a system of levers and 55 connecting-rods fixed to an upright rock-shaft situated in the wheel-house, and by which the rudder is placed under the control both of the man at the wheel and the pilot on the bridge or another part of the vessel. This mechanism is illustrated by Figs. 1, 2, 4, 5, 6 of the drawings.

The upright rock-shaft *J* turns in sockets *f f* in the floor and ceiling of the wheel-house, and has a hand-lever, *K*, fixed to it 60 at a convenient height and position. A second lever, *K'*, is situated upon the roof of

the wheel-house, and is secured directly to the upper end of the shaft *J*, that projects through the roof; or, where the lever *K'* is required to be used in another location at a 70 greater distance from the wheel, connecting-belts or wire ropes *k* and two grooved pulleys, *l l*, one of them with the lever *K'* upon it, can be employed, as shown in Fig. 3. By means of these two levers, *K K'* the rock-shaft is 75 moved, and its motions are communicated to the lower ends of the upright levers *M M'* through the connecting-rod *L* and the short arm *m*, fixed on the shaft *J*. The levers *M M'* are pivoted, at *n n*, to a fulcrum-bar, *h*, and 80 embrace the shaft *a*. Between them is placed a loose axial sleeve, *p*, through which the shaft *a* turns freely, and through them project the posts *o o*, that extend from opposite sides of the sleeve *p*. These posts *o o* are screw-threaded upon their ends to receive the nuts *q q*, and after passing through the levers *M M'* they receive and hold the cross-bars *N N*, with the shoes or segment-plates *r r'*, that surround and grasp between them the circular flanges 85 *O O* on the inner faces of the clutches *I*. The pressure of these curved plates *r r'* is produced and regulated by the nuts *q* and the springs *s s*, which, by bearing upon the arms *N N*, hold the curved shoes *r* in contact with the flanges *O*. Thus the clutches and their shaft *a* are 90 kept stationary, except at the times when either one of the clutches is to be thrown against a pulley, *G* or *G'*, to turn the shaft. At such times the flanges *O* are relieved from the pressure of the shoes *r r'* by the action of the pivoted plate *P*, between the lower ends of the upright levers *M M'*, for when the 95 clutches are to rotate it is necessary to lift and hold back the brakes. This plate *P*, to which 100 the end of the rod *L* is connected by the pin *k*, turns on a pivot, *t*, and by the movement of the rod it is thrown and held out of a perpendicular. It has two bosses, *u u*, in the 105 faces of which are the notches or wedge-shaped slots *w w*, and into these notches the teeth or nibs *x x* (of corresponding shape) on the ends of the levers *M M'* are pressed and held by the 110 action of the springs *s s*.

When the plate *P* occupies a perpendicular 115 position the nibs or teeth of the levers rest in the notches *w w*; but when it is caused to take a diagonal position the teeth are raised out of the notches *w* by the turning of the plate, and the ends of the levers *M* are spread 120 apart and held a sufficient distance to lift the brakes *r r'* clear of the flanges on the sides of the clutches. As long as the plate *P* is held in such diagonal position the teeth *x x* are 125 kept out of their seats in the bosses *u u* and the brakes are held back; but as soon as the hand-lever operating the connecting-rod *L* is released the pressure of the springs *s s* against the levers *M M'*, forces the teeth *x x* back into their notches and permits the brakes *r r'* to 130 close against the flanges *O*. At the same time the plate *P* is brought back into its position

in perpendicular line with the levers M. This will be all clearly understood by referring to Figs. 4, 5, 8, 10 of the drawings.

Whenever the rock-shaft J is turned by the hand-levers the connecting-rod L is caused to move the upright levers M upon their fulcrum-point h into a more or less inclined position, and by this means to press the end of the shifting-sleeve p, and also move one or other of the sets of brake-shoes laterally against the face of a clutch, I or I', and hold it against the pulley next to it. As long as pressure against the hand-lever is maintained the levers M will keep the clutch in action and the shaft a will revolve; but the movement required to throw the parts into and out of working contact is so slight that as soon as the hand-lever is released the tendency of the levers M M to return to their normal position through the pressure of the springs s s will throw on the brakes at the same time that the clutch in action is moved from its pulley. Thus the connecting-rod L, while it moves the levers M M toward one or the other of the clutches and produces their required shifting movements toward the pulleys G G', also acts at the same time to lift and hold up the brakes r r by turning the plate P into a diagonal position.

By reference to Figs. 1, 4, and 11 of the drawings it will be seen that the fulcrum-bar h is not stationary, but is made to travel upon a screw-shaft, Q. This screw-shaft is placed above and in line with the shaft a, and is geared with it by means of the pinion y and the gear-wheel R. Any movement of the steering-wheel therefore produces a corresponding rotation of the shaft Q, and the fulcrum-point h is caused to travel and change its position on the shaft simultaneously with the rudder's movements, and either toward or away from a vertical line, 1 2, on which the posts or centers o o are situated. When the fulcrum-bar h has traveled from one end to the other of the screw-shaft Q the rudder has moved from its extreme point port to its extreme position starboard, or vice versa, according to the direction of movement. This shifting of the fulcrum-point h turns the levers about upon the center posts, o o, and throws the position of the ends of the levers and their plate P either nearer to or farther away from the line of the upright rock-shaft J; and as the length of the connecting-rod L is a fixed one this movement of the point of connection affects the angular position of the short arm or lever fixed on the upright shaft, and thus changes the angle of the hand-levers K with respect to the longitudinal axis of the vessel or a fixed index-mark. The rudder of the vessel and the hand-levers K K' are by this means caused to move in unison, and the position of the one always coincides with that occupied by the other.

As the apparatus is arranged in Figs. 2 and 4, the rotation of the shaft a in the direction 3 will turn the steering-wheel in the direction 4 and move the rudder to port. At the same

time the rotation of the screw-shaft Q will move the fulcrum-point in the direction 5 and throw the levers into the angular position shown in Figs. 4 and 11 by the broken lines. By thus moving the point t farther away the upright shaft J is slightly rotated by the movement of the connecting-rod L, and the hand-lever follows the movement of the rudder and indicates its position.

The fulcrum-bar h on the screw-shaft has an adjustable stop, z, at either side of its dependent end, which, when the bar h reaches the limit of its travel on the shaft Q, will strike and press against the face of the clutch (I or I') next to it, and so move away the opposite clutch from its pulley (both clutches being connected so as always to move laterally together on their shaft a) and stop the rotation of the shaft a. This constitutes an automatic means for throwing the apparatus out of action as soon as the rudder has reached either extreme position to prevent straining or breaking the rudder or parts of the working mechanism through carelessness. Fixed stops for the same purpose can be also placed upon each side of the hand-levers K K' to prevent them from being pressed over too far.

Instead of making the hand-levers K serve as indicators of the position of the rudder a fixed pointer on the shaft J and a graduated arc situated in front of it can be employed in connection with the rock-shaft to show and record more accurately the position of the rudder.

By having additional hand-levers K' K' located on the deck or bridge convenient to the captain's or pilot's accustomed station, and connecting them positively with the actuating-shaft of the apparatus in the wheel-house, as before described, the entire apparatus is placed under the control of the officer on the bridge, and, while the position of the rudder is always indicated to him, a means is also provided for controlling the movements of the wheel below in the pilot-house and for checking any change made by the man at the wheel through haste or carelessness. This indicating mechanism can be readily applied to the steering-wheel of any vessel without the employment of the actuating-pulleys and locking mechanism that are herein connected with it.

Where the belt H cannot be driven with advantage or convenience from the main engine of the vessel an auxiliary motor can be employed, and the surplus power thereof can be used for hoisting, pumping, &c, thereby making the apparatus more economical to work.

The gear-wheel can be made in segments, if required, that it may be placed in position and bolted together without removing the steering-wheels. The driving-pinion b is made to slide upon its shaft also, so that it can be thrown into and out of gear with the steering-wheel gear when desired. This permits the steering-wheel to be turned by hand at any time.

The power of the brakes r r' is regulated by compressing the springs more or less, and the

amount of pressure required to hold the steering-wheel at rest can be varied, so that the brakes may yield and allow the wheel to turn and relieve the rudder just enough to prevent any breaking of the parts in a heavy sea.

Having thus fully described my invention, what I claim, and desire to secure by Letters Patent, is—

1. A power steering apparatus for vessels, consisting of the following parts or elements: a steering drum or axle having a gear-wheel secured thereon, a horizontal shaft geared into said wheel, a set of loose pulleys revolved continuously and independently of each other in opposite directions upon said shaft, and a means for locking either one of said pulleys fast upon the horizontal shaft at any time, substantially as herein described, whereby the motion of either one of said pulleys is communicated to the steering-drum.
2. The combination in a power steering apparatus for vessels, of a horizontal rotating shaft geared into the steering wheel or drum, a set of loose pulleys upon said shaft having a continuous rotary motion in opposite directions to each other, and a set of friction disks or clutches fixed to said shaft but capable of being moved laterally on said shaft toward and away from either one of the revolving pulleys, whereby the said shaft can be locked to and receive the rotation of either one of the said pulleys at will, substantially as herein described, for the purposes set forth.
3. The combination, in a power steering apparatus, of a horizontal rotating shaft geared into the steering wheel or drum, a set of loose pulleys having a continuous rotary motion, as described, upon said shaft, and a set of friction disks or clutches fixed to said shaft between the said revolving pulleys, and also connected to each other, to move simultaneously and together upon their shaft, whereby either one of said clutches is moved away from its pulley and out of action therewith before the other clutch can engage with the pulley adjacent thereto, substantially as and for the purpose set forth.
4. The combination, in a power steering apparatus, of a horizontal rotating shaft geared into the steering wheel or drum, and having a set of friction-clutches fixed thereon, but capable of a laterally-shifting movement in both directions, a set of loose pulleys having a continuous rotary motion, one in opposite direction to the other, upon said shaft, and located one in front of each of the said clutches, a means for shifting the said clutches simultaneously together upon said shaft toward and away from their pulleys, and a means for holding the said clutches and their shaft at rest at any point when the said clutches and pulleys are not in working contact, all substantially as herein described.
5. In combination, the laterally-moving clutches I I', the levers M M', pivoted to a fulcrum, h, the loose axial sleeve p, with its posts o o, the cross-arms N N', with shoes r r', the

connecting-rod L, attached to the free ends of the levers M M', and the actuating rock-shaft J, substantially as herein set forth, and constituting a means for shifting the said clutches, as described.

6. In combination, the laterally-moving clutches I I', with flanges O O, the levers M M', the screw-shaft Q, geared into the steering wheel or drum and rotating in unison with it, the traveling fulcrum-bar h, the axial sleeve p on the shaft a, the cross arms N N, with shoes r r', the springs and nuts q s, the pivoted plate P, and the connecting-rod L, attached thereto, substantially as described, to operate for the purpose set forth.

7. The rock-shaft J and a means for turning the shaft simultaneously and in unison with the steering wheel or drum of a vessel when said shaft has a lever, arm, or other means fixed thereto for indicating its movements, substantially as described, all combined for the purposes set forth.

8. The combination, with a steering apparatus for vessels, of the rock-shaft J, a means for operating the said shaft to turn simultaneously and in unison with the steering wheel or drum, and the auxiliary lever or arm K', connected to said shaft, substantially as described, and operating for the purposes set forth.

9. In combination with the levers M M', having cross-arms N N', with shoes r r', and the sleeve p, with the springs and nuts s q, the fulcrum-bar h, for connecting the said levers at one end, and a means, substantially as herein described, for spreading them apart at their opposite ends, for the purposes set forth.

10. In combination with the levers M M', pressed toward each other by springs s, and having a fulcrum-joint at one end and angular teeth or nibs x x on the inner face of their opposite ends, the pivoted rocking plate P, provided with bosses u u, in which are diametrical notches w w, to receive the said nibs x x, and connected with said levers M M' by a pin or pivot which passes through the said ends and through the plate P, and the lever L, for operating said plate, all constructed and applied to operate as set forth.

11. In combination with the shaft a, geared into the drum or axle of a steering-wheel, and carrying the continuously-revolving pulleys, and the clutches I I, constructed substantially as described, the traveling fulcrum-bar h upon the screw-shaft Q, having stops z z, which are adjustable in length on the sides of the bar adjacent to the faces of the clutches, said shafts a and Q being geared together to operate the fulcrum-bar, substantially as herein described, for the purpose set forth.

In testimony that I claim the foregoing I have hereunto set my hand and seal this 25th day of January, 1879.
